US00D989780S

(12) **United States Design Patent** (10) Patent No.: US D989,780 S
Havranek et al. (45) Date of Patent: ** Jun. 20, 2023

- (54) **DISPLAY SCREEN WITH GRAPHICAL USER INTERFACE**

(71) Applicant: **TeleTracking Technologies, Inc.**,
Pittsburgh, PA (US)

(72) Inventors: **Thomas Havranek**, Baden, PA (US);
Yujie Cong, Bridgeville, PA (US);
Thomas Perry, DuBois, PA (US);
David Seger, Franklin, TN (US);
Henok Wondem, Nashville, TN (US);
Raja Chava, Bethel Park, PA (US);
Spencer Jameson, Antioch, TN (US);
Russell Tucker, Pittsburgh, PA (US)

(73) Assignee: **TELETRACKING TECHNOLOGIES, INC.**, Pittsburgh, PA (US)

(**) Term: **15 Years**

(21) Appl. No.: **29/786,030**

(22) Filed: **May 28, 2021**

(51) **LOC (14) Cl.** **14-04**

(52) **U.S. Cl.** ..... **USPC** **D14/485**

(58) **Field of Classification Search**
USPC **D14/485**

See application file for complete search history.

CLAIM

The ornamental design for a display screen with graphical user interface, as shown and described.

DESCRIPTION

The FIGURE is a front view of a display screen with a graphical user interface showing the new design. The broken lines of uneven length show the display screen and form no part of the claimed design. The broken lines of even length shown in the drawings illustrate portions of the display screen with graphical user interface that form no part of the claimed design.
